(57) **CLAIM**

The ornamental design for an electronic cigarette atomizer, as
shown and described.

DESCRIPTION

FIG. 1 is a front elevational view of a first embodiment of an
electronic cigarette atomizer;

FIG. 2 is a left side elevational view of the first embodiment
of the electronic cigarette atomizer;

FIG. 3 is a top plan view of the first embodiment of the
electronic cigarette atomizer;

FIG. 4 is a bottom plan view of the first embodiment of the
electronic cigarette atomizer;

FIG. 5 is a first perspective view of the first embodiment of the
electronic cigarette atomizer;

FIG. 6 is a second perspective view of the first embodiment of
the electronic cigarette atomizer;

FIG. 7 is a front elevational view of a second embodiment of
the electronic cigarette atomizer;

FIG. 8 is a rear elevational view of the second embodiment of
the electronic cigarette atomizer;

FIG. 9 is a left side elevational view of the second embodiment
of an electronic cigarette atomizer;

FIG. 10 is a right side elevational view of the second embodiment
of the electronic cigarette atomizer;

FIG. 11 is a top plan view of the second embodiment of the
electronic cigarette atomizer;

FIG. 12 is a bottom plan view of the second embodiment of
the electronic cigarette atomizer;

FIG. 13 is a first perspective view of the second embodiment
of the electronic cigarette atomizer; and,

FIG. 14 is a second perspective view of the second embodiment
of the electronic cigarette atomizer.

The broken lines in the drawings depict parts of the electronic
cigarette atomizer that form no part of the claimed design.
